SACK CHUTE AND SWITCH

William M. Brenchley, Stockton, Calif.

Application April 16, 1938, Serial No. 202,482

7 Claims. (Cl. 193—31)

This invention relates to ship loading apparatus and particularly to a device to facilitate the loading of sacked produce such as grain into the hold of a vessel.

One of the major objects of my invention is to provide a flexible spout adapted to depend into the hold from adjacent the hatch, and which is especially designed to handle sacked grain and the like (as distinguished from bulk grain) without danger of the sacks bursting open as they drop down the spout and negotiate the one or more relatively sharp bends usually given the spout to break the speed of descent of the sacks. To speed up loading operations, two of the spouts are employed, and another important object of the invention is to provide a chute from which the spouts depend, and to arrange an automatically functioning means on the chute so that with the sacks deposited in single file order on the chute at its end furthest from the spouts, said sacks will, in the normal operation of the device, be automatically diverted into the two spouts in alternating order. At the same time, the device may be adjusted if desired so that the sacks will all pass into only one of the spouts.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a side elevation of the complete apparatus.

Figure 2 is an enlarged side elevation partly in section, of the chute structure.

Figure 3 is a top plan view of the same.

Figure 4 is an enlarged fragmentary section of a spout at its upper end showing the mounting and supporting means for the spout sections.

Figure 5 is a fragmentary side view showing the releasable connection means between a spout section and its supporting chain.

Figure 6 is a plan view of a spout section detached.

Referring now more particularly to the characters of reference on the drawings, the chute structure comprises a main chute portion 1 having sides 2 somewhat deeper than the thickness of a loaded sack. The chute slopes down to one end and is supported from a vertically adjustable framework 3 which rests on the hatch cover

of the hold into which the sacks are to be loaded. The width of the portion 1 is somewhat greater than the width of a sack. At the lower end of the main or initial portion 1, the chute flares out to form a wide portion 4 whose width is more than double that of portion 1, which portion 4 communicates with a pair of laterally spaced chute branches 5 at the lower end of the chute and which terminate in downwardly facing discharge spouts 6. These spouts are of oval form, symmetrical to and slightly larger than the cross sectional area of a loaded sack, with their major axis extending transversely of the chute. One branch or leg is longer than the other, so that the spouts are offset from each other both transversely and longitudinally of the chute, for the purpose which will be seen.

Disposed in the chute and extending from adjacent the inception of the flaring portion 4 to the inception of the branches 5 is a swinging gate unit. This comprises a forward member 7, substantially in the form of a heavy plate set on edge, and pivoted on a pin 8 whose axis is at right angles to the bottom of the chute and which is supported by cross bars 9 rigid with the chute above and below the same.

The rear member 10 of the gate is also pivoted on the pin 8 for swinging movement independently of the member 7, the sides of member 10 flaring rearwardly from the pin so that they are not normally in line with the sides of member 7. The member 10 is yieldably maintained in symmetrical relation to member 7 by a leaf spring 11 set on edge and secured at its rear end on the member 10 at its rear end. At its forward end, spring 11 engages a pin 12 upstanding from a short arm 13 overhanging the adjacent end of member 10 and rigid with member 7.

At its forward end, member 7 is provided with a bumper roller 14 adapted to bear against either side wall of the chute. Guard elements 15 in the chute ahead of the roller prevent any possible catching of a sack in the corner formed between the roller and the adjacent side wall of the chute. A snap action device 16 which includes a spring 17 whose tension may be adjusted as clearly indicated in Fig. 2, extends between the forward end of the gate and the chute structure rearwardly of the gate, said device being of course above the gate and pin 8.

With the gate in either position, the member 7 is substantially parallel to the opposite side of the flaring chute portion 4 and is of course spaced therefrom a distance greater than the width of a

sack. The member 10 on the corresponding side however projects into the chute so that its rear end is considerably closer to said side of the chute than the width of a sack. As a result, a sack sliding down the chute is deflected by the member 7 and then engages said member 10. Since the spring 17 is ordinarily weaker than spring 11, the gate as a whole is swung by the sack until the latter can pass by the obstruction offered by member 10 and enter the adjacent branch 5 and spout 6.

When the gate is deflected sufficiently to pass the sack however, it is then beyond a dead center position relative to the snap action device and the latter then functions to throw the gate so that it then closes the branch 5 just used, and diverts the next sack into the other branch, with a subsequent reversal of the gate in the same manner to its original position.

20 The sacks will thus be delivered alternately to the two branches provided the sacks are fed into the chute with some spacing therebetween as is customary. If however a sack should happen to engage the forward end of the gate and prevent 25 swinging thereof before the sack ahead has cleared the gate member 10, the latter will then be deflected by the sack against the resistance of spring 11 to allow the sack to pass, and the subsequent sack will also enter the same chute branch. 30 This however is immaterial in an apparatus of this character, in which perfect alternation is unnecessary.

If intentional feeding into only one chute branch is desired, the above result may be obtained by tensioning spring 17 until its resistance is greater than that of spring 11. This result is had by reason of the fact that the leverage exerted on member 7 by the snap action device 16 is then greater than the leverage exerted on short arm 13 by spring 11 and thus the gate member 10 may be deflected laterally by a passing sack without moving the gate member 7 past dead center and all sacks will feed into the same branch.

45 In connection with the chute unit above described, I employ a novel form of flexible spout adapted to depend to any necessary depth into the hold of the vessel from the spouts 6.

These flexible spouts, of which there are of 50 course two, each comprises a plurality of relatively short spout sections 18 of tapering form, whose cross sectional shape is shown in Fig. 6, and which is the same as that described in connection with spouts 6, which project loosely into 55 the topmost spout sections as shown in Fig. 4.

Each spout, whose total length may exceed forty feet, is supported independently of the chute unit by chains 19 at the wide sides of the spout sections, which chains depend from and are 60 supported by frames 20 removably resting on the hatch cover.

The chains include snap hooks 21 at intervals, so that lengths of the spout may be easily removed as the hold fills up, and a shorter spout is wanted. In order to facilitate repairing of the spout, each section 18 is releasably connected to the chains by studs 22 projecting outwardly from the sections at the rim thereof and extending through adjacent links of the chains, as shown in Figs. 65 4 and 5.

70 The chains are held against undesired disengagement from the studs by suitable means such as cotter pins 23 through the studs. The spout sections have a loose telescoping fit with each other as shown, so that the spout as a whole 75 may be easily flexed or bent in any desired di-

rection, both to place the discharge end of the spout at the necessary loading point in the hold and also to enable speed retarding bends to be formed in the spout at intervals. To facilitate the formation of such bends, which may need to be quite abrupt or of small radius, a plurality of the sections 18, at intervals in the length of the spout, are made relatively short as clearly shown in Fig. 1.

By reason of the double offsetting of the chute spouts 6 with which the flexible depending spouts register, said spouts may be deflected in the same or in opposite directions, either transversely or longitudinally of the chute unit, without interfering with each other.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention as defined by the appended claims.

Having thus described my invention, what I claim as new and useful and desire to secure by Letters Patent is:

1. In a chute assembly for two-way distribution of individual articles, said assembly including a chute to receive articles in single file order, a pair of chute branches at one end of said chute, a gate disposed lengthwise in the chute adjacent the chute branches, a pin pivoting the gate intermediate its ends for swinging movement in a plane laterally of the chute, a snap action spring device applied to the gate to yieldably hold the same in angular relation to the chute and in position to engage and divert an article moving along said chute into one of the branches, the opposite sides of the gate rearwardly of the pin flaring from each other so as to project into the path of an article diverted into either branch sufficiently to cause engagement and continued movement of the article with the corresponding flaring side to swing the gate past a dead center position; the portion of the gate rearwardly of the pin being in the form of a member pivoted on said pin for swinging movement independently of the remainder of the gate, and another spring of greater tension than the spring of the snap action device acting on said member to yieldably resist swinging movement thereof.

2. A device as in claim 1 in which the spring of said snap action device is capable of adjustment to increase the tension thereof to an extent in excess of that of said other spring.

3. In a chute assembly for two-way distribution of individual articles, said assembly including a chute to receive articles in single file order, a pair of chute branches at one end of said chute, a gate disposed in the chute adjacent the chute branches, means pivoting the gate for swinging movement laterally of the chute, and a snap action spring device applied to the gate to yieldably hold the same in angular relation to said chute and in position to engage and divert an article moving along said chute into one of the branches, a portion of the opposite sides of the gate flaring from each other so as to project sufficiently into the path of an article diverted into either branch whereby upon engagement of said article with the corresponding flaring side portion of the gate and continued movement of said article to swing the gate past a dead center position; said flaring

portions of the sides of the gate being separate from the remainder of the gate, means mounting said side portions of the gate for lateral swinging movement independently of said remainder of the gate, and means yieldably resisting such independent swinging movement of said side portions and with a force greater than that exerted by the spring of the snap action device.

4. In a chute assembly for two-way distribution of individual articles, said assembly including a chute to receive articles in single file order, a pair of chute branches at one end of said chute, a gate disposed in the chute adjacent the chute branches, means pivoting the gate for swinging movement laterally of the chute, and a snap action spring device applied to the gate to yieldably hold the same in angular relation to said chute and in position to engage and divert an article moving along said chute into one of the branches, a portion of the opposite sides of the gate flaring from each other so as to project sufficiently into the path of an article diverted into either branch whereby upon engagement of said article with the corresponding flaring side portion of the gate and continued movement of said article to swing the gate past a dead center position; said flaring portions of the sides of the gate being separate from the remainder of the gate, means mounting said side portions of the gate for lateral swinging movement independently of said remainder of the gate, and another spring mounted in connection with said side portions and yieldably resisting such independent movement thereof and with a force greater than that exerted by the spring of the snap action device.

5. A device as in claim 4 in which the spring

of said snap action device is arranged for adjustment to increase the tension thereof to an extent that the force exerted thereby is greater than the force exerted by said other spring mounted in connection with said side portions.

6. A chute assembly for two-way distribution of individual articles, said assembly including a chute to receive articles in single file order, a pair of chute branches at one end of said chute, a gate disposed in the chute adjacent the chute branches, said gate comprising separate front and rear sections pivoted together at adjacent ends for relative swinging movement laterally of the chute, a snap action spring device applied to the front section to yieldably hold the same in angular relation to said chute and in position to engage and divert an article moving along said chute into one of the branches, the rear section of said gate having rearwardly flaring sides, and means connected between the front and rear sections and maintaining the rear section in laterally yieldable but normally symmetrical relation to the front section, said means upon lateral movement of the rear section exerting an opposite and greater rotating force on the front section than that of the spring of the snap action device.

7. A device as in claim 6 in which said means comprises a longitudinally extending leaf spring disposed on edge and secured at its rear end on the rear section, the forward end of said spring being formed as a fork, an arm on the front section extending rearwardly of the gate pivot and above said rear section, and a pin upstanding from the rear end of said arm, the fork straddling said
